UNITED STATES PATENT OFFICE.

FRANK E. CROTON, OF DALLAS, TEXAS.

WELL-CLEANING DEVICE.

1,400,030.

Specification of Letters Patent. Patented Dec. 13, 1921.

Application filed January 14, 1921. Serial No. 437,300.

To all whom it may concern:

Be it known that I, FRANK E. CROTON, a citizen of the United States, residing at Dallas, in the county of Dallas and State of Texas, have invented certain new and useful improvements in Well-Cleaning Devices, of which the following is a specification.

This invention relates to new and useful improvements in well cleaning devices.

10 The object of the invention is to provide a well cleaning device which involves a simple and practical packer construction of the expansion type. A particular feature resides in an elastic packing element constructed to first be expanded against the inner wall of the screen pipe and then to permit the fluid to discharge axially of the fluid supply pipe so that the washing and cleaning operation may be carried out.

20 A construction designed to carry out the invention will be hereinafter described together with other features of the invention.

The invention will be more readily understood from a reading of the following specification and by reference to the accompanying drawings, in which an example of the invention is shown, and wherein:

Figure 1 is a vertical longitudinal sectional view of a well casing showing in side elevation a well cleaning device constructed in accordance with my invention,

Fig. 2 is an enlarged longitudinal vertical sectional view, and

Fig. 3 is a cross sectional view on the line 3-3 of Fig. 2.

In the drawings the numeral 10 designates an ordinary well screen having the usual perforations 11 and any screen structure as the ordinary wire windings 12. The usual line or string of pipe 13 is connected with a cleaner section 14 by means of the usual collar 15. On the lower end of the section 14 a plug 16 is mounted. The lower end of the section 14 is screw-threaded at 17 and its upper end is screw-threaded at 18. Near each end of the section, an elastic packing sleeve 19 is mounted. As both of the sleeves and their respective parts are alike, a description of one will suffice for both.

50 A collar 20 is mounted on a screw-threaded portion 17 and has a dished face 21 and an annular cutting flange 22, the latter being for scraping the inside of the casing 10.

The cylindrical sleeve 19 is preferably 55 formed of rubber or like material, but could

be made of any elastic substance. At one end the sleeve has an inwardly directed annular flange 23. A collar 24 is threaded on the portion 17 and engages the inner face of the flange 23 which latter has its outer face 60 in engagement with the dished portion 21 of the collar 20. The face of the collar 24 which contacts with the flange 23 is concaved and thus the said flange will be clamped between the two collars and confined against radial displacement by the concaved faces. The outer edge of the collar 24 is rounded where the sleeve contacts so as not to injure the latter.

At its opposite end the sleeve 19 has an 70 inwardly directed annular lip 25 which closely embraces the pipe section 14. The edge of the lip is reduced and rounded so as to be slightly compressed about the pipe. Within the sleeve 19 the pipe section 14 has 75 a plurality of perforations or apertures 26 through which the water or other fluid from the pipe 14 may flow into the sleeve. As before stated the sleeves at each end of the section 14 are substantially the same, the 80 only difference being that instead of the plug 16, the collar 15 engages the collar 20 of the upper sleeve. The pipe 14 is not perforated between the sleeves.

In using the device the section is lowered 85 into the well screen to the point desired to be cleaned. Water or any other cleaning fluid under pressure is supplied from a suitable source through the pipe 13 from the top of the well to the section 14. The fluid 90 can escape only through the perforations 26 and fills the cylindrical sleeve 19. This fluid being under pressure seeks an exit and the sleeves being elastic, expand under the influence of the pressure and come into contact with the inner side of the casing 10 as is shown in dotted line in Fig. 2. When this is accomplished the fluid cannot pass above or below the packers but must pass from the sleeve through the opening provided by the expanded lips 25. The fluid discharged from the sleeve passes out through the perforations 12 of the casing and washes the screen as is obvious. As long as the pressure is maintained the sleeves 95 will remain expanded. When the pressure is relieved the sleeves will return to their normal form and the device may be easily withdrawn from the well.

Changes in the dimension and design of 110

the device may be made within the scope of the invention and modifications made without departing from its spirit.

What I claim, is:

- 5 1. In a well cleaning device, a pipe section, elastic packing elements mounted on the section and spaced apart, the section having perforations within the packing elements and being imperforate between the 10 packing elements, the packing elements being expandible, whereby the fluid passing through the perforations will create pressure and expand said elements against the side of the well casing and then discharge 15 from the elements into the space between said elements.
2. In a well cleaning device, a pipe section, cylindrical packing elements mounted on the section and having their adjacent 20 ends free to expand, said elements having internal pressure spaces, said pipe section having perforations communicating with the spaces of the elements and being imperforate between the elements, whereby the 25 fluid from the pipe section enters the packing elements and first expands the same and then escapes between the elements.
3. In a well cleaning device, a pipe sec-

tion, and an elastic hollow packing sleeve having one end secured to the section and the other end free to expand, but normally embracing the pipe section, the pipe section having perforations within the packing sleeve to supply fluid to expand the sleeve prior to its discharge therefrom.

35 4. In a well cleaning device, a pipe section having a threaded portion, a pair of collars mounted on the threaded portion of the pipe, and an elastic packing sleeve considerably larger internally than the section and having one end clamped between the collars and the other end contracted and normally embracing the pipe section.

40 5. In a well cleaning device, a pipe section having its lower end obstructed and screw threaded at each end, a pair of collars at each end having their adjacent faces concaved, hollow rubber sleeves each having an inwardly directed annular portion clamped between the concaved faces of the collars, and an annular lip at each end of each sleeve 45 embracing the pipe section, the pipe section having perforations within the sleeves and being imperforate between the sleeves.

50 In testimony whereof I affix my signature. 55
FRANK E. CROTTO.
